UNITED STATES PATENT OFFICE

2,465,178

LAPPING MACHINE

Peter J. Sommer, Jr., Chicago, Ill., assignor to Size Control Company, Chicago, Ill., a copartnership

Application September 20, 1946, Serial No. 698,115

3 Claims. (Cl. 51—88)

1

This invention relates to improvements in precision machine tools. More particularly it pertains to a centerless lapping machine for precision finishing of cylindrical work pieces by means of two rollers each traveling in the same direction, the cylindrical surfaces of each roller being so spaced apart that they simultaneously support as well as lap finish such work pieces therebetween, and the provision of such a machine is a principal object of the invention.

More specifically, an object of the invention is to provide a centerless lapping machine for precision finishing of cylindrical work pieces in which two lap cylinder rollers are utilized by being mounted upon rotatable shafts, the rollers having their cylindrical surfaces adjustably disposed and relatively movable with respect to each other, one of the rollers being of greater diameter than the other, and rotatable means connected to the shafts to drive the rollers at different rates of speed and in the same direction, the rollers being so spaced that they will simultaneously support as well as lap finish cylindrical work pieces placed between them.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Fig. 1 is a transverse elevational view illustrating a preferred embodiment of the invention;

Fig. 2 is a top plan view of the lapping rollers; and

Fig. 3 is a rear view showing the arrangement of the driving mechanism for the lapping rollers.

Referring more particularly to the drawings, there is shown generally at 10 a centerless grinding apparatus mounted within a safety cabinet indicated generally at 11.

Two lapping cylinder rollers 12 and 13, preferably of unequal diameter are mounted upon rotatable shafts 14, 14. These rollers have their cylindrical surfaces adjustably disposed with respect to each other. That is, the shaft to which the roller 12 is connected is mounted in fixed rotatable position, whereas the shaft and journal bearing members for holding the roller 13

2

are movable toward and away from the roller 12 by means of, for example, a screw arrangement such as that depicted at 15. These two rollers are mounted within the cabinet 11 on a platform 16 immediately beneath a top cover member 17 of the cabinet 11. The rollers are exposed in such a manner that only their operating surfaces project above the top of the cover member. Adjacent each end of each roller there is a well 18 in the cover member for ready removal of a work piece 19 as will more fully appear hereinafter. The cabinet 11 encloses the remainder of the apparatus in such a manner as to provide safety in operation against accidents.

15 On a base platform 20 in the bottom of the cabinet 11 there is utilized a motor 21 for actuating the lapping rollers 12 and 13. Preferably, this motor drives a belt 22 which in turn drives a pulley 23 secured to a shaft 24 mounted in a bearing 25 carried by an intermediate platform 26 in the cabinet 11.

Disposed in parallel relationship to the shaft 24 is a countershaft 27, mounted in a bearing 28 on the platform 26 and underlying the rollers 12 and 13. The countershaft 27 is driven from a pulley 29 on the shaft 24. A belt 30 passes around the pulley 29 to a pulley 31 which in turn is secured to the countershaft 27.

Also mounted on the countershaft 27 is a large pulley 32 as well as a smaller pulley 33. By means of a belt 34 the larger pulley 32 actuates a pulley 35 connected to the shaft 14 carrying the lap roller 12. The smaller pulley 33, by means of a belt 36, actuates a pulley 37 secured to the shaft 14 carrying the lap roller 13. By this arrangement both of the lap rollers are actuated at different rates of speed and in the same direction.

It will be observed that all of the bearings are resiliently mounted, for example, on rubber pads. 40 This, in conjunction with the driving belts, eliminates chattering and obtains smooth surfaces on work pieces to be lap finished, eliminating chatter marks therefrom.

The means for adjusting the movement of the 45 smaller diameter lap roller 13 should be such that the space between its surface and the surface of the larger lap roller can be adjusted as desired. That is, it may be desirable to have the spacing at one end slightly greater than at the 50 other end between the surfaces so that a work piece 19 (Fig. 2) can be moved in either direction from one end to the other and readily picked from between the operational surfaces as it reaches the well in the top cover of the cabinet 55 11 adjacent the ends of each of the lap rollers

12 and 13. As illustrated in Figs. 1 and 2 the adjusting screws 15 may be rotatably supported in angle brackets 38 which are secured on the platform 16 immediately in front of the bearing supports 39. The screws 15 have their ends in threaded engagement with the bearing supports 39 and the bearing supports 39 are in sliding dovetail engagement with guide members 49. There is sufficient play in the bearings and the sliding bearing supports to permit the slight angular movement of the shafts required for adjusting the rolls 12 and 13 as described.

It should be noted that it is within the contemplation of the invention to utilize the foregoing machine to lap grind other gages such as the interior surfaces of ring gages as well as thread gages and the like.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent is:

1. In a centerless lapping machine, for precision finishing of cylindrical work pieces, the improvement comprising two lap cylinder rollers of unequal diameter each mounted upon shafts, which rollers have their cylindrical surfaces adjacently disposed with respect to each other, the larger of said rollers having its shaft journaled in fixed position and the smaller of said rollers having its shaft journaled in movable bearings, said bearings being adapted to be adjusted toward and away from said larger roller, rotatable means connected to said shafts to drive said rollers at different rates of speed and in the same direction, said rollers being so spaced that they will simultaneously support as well as lap finish said cylindrical work pieces therebetween, and said smaller roller being angularly adjustable with respect to said larger roller so that the space between both cylindrical surfaces is such that a rotating work piece will be carried along said cylindrical surfaces from one end of each roller to the other end thereof.

2. In a centerless lapping machine, for precision finishing of cylindrical work pieces, the improvement comprising two lap cylinder rollers each mounted upon rotatable shafts, which rollers have their cylindrical surfaces adjacently disposed and which rollers are relatively spaceable with respect to each other, one of said rollers being of greater diameter than the other, and rotatable means, including a driven countershaft carrying two pulleys of unequal diameter, the larger of said pulleys being connected to the shaft carrying the lap roller of greater diameter by means of a belt to rotate the same, and the smaller of said pulleys being connected to the lap roller of smaller diameter by means of a belt to rotate the same, both of said rollers being actuated at different rates of speed and in the same direction, said rollers being so spaced that they will simultaneously support as well as lap finish said cylindrical work pieces therebetween.
3. In a centerless lapping machine, for precision finishing of cylindrical work pieces, the improvement comprising two lap cylinder rollers each mounted upon rotatable shafts, which rollers have their cylindrical surfaces adjacently disposed and which rollers are relatively spaceable with respect to each other, one of said rollers being of greater diameter than the other, rotatable means connected to said shafts to drive said rollers at different rates of speed and in the same direction, said rollers being so spaced that they will simultaneously support as well as lap finish said cylindrical work pieces therebetween, and all of said rotating parts being resiliently mounted to eliminate vibration, thereby inhibiting the imparting of chatter marks to said work pieces.

PETER J. SOMMER, JR.
